UNITED STATES PATENT OFFICE.

WINFIELD L. DINSMOOR, OF LONGBEACH, CALIFORNIA.

ULLAGE-ROD.

946,695.

Specification of Letters Patent. Patented Jan. 18, 1910.

Application filed May 6, 1909. Serial No. 494,247.

To all whom it may concern:

Be it known that I, WINFIELD L. DINSMOOR, a citizen of the United States, residing at Longbeach, in the county of Los Angeles and State of California, have invented 5 a new and useful Ullage-Rod, of which the following is a specification.

The objects of the invention are, generally, the provision in a merchantable form, 10 of a device of the above mentioned class, which shall be inexpensive to manufacture, facile in operation, and devoid of complicated parts; specifically, the provision of an ullage rod provided with liquid receiving 15 openings of novel and improved construction; other and further objects being made manifest hereinafter as the description of the invention progresses.

The invention consists in the novel construction and arrangement of parts herein- 20 after described, delineated in the accompanying drawings, and particularly pointed out in that portion of this instrument wherein patentable novelty is claimed for certain 25 distinctive and peculiar features of the device, it being understood, that, within the scope of what hereinafter thus is claimed, divers changes in form, size proportions and minor details of the structure may be made 30 without departing from the spirit or sacrificing the advantages of the invention.

Similar numerals of reference are em- 35 ployed to denote corresponding parts throughout the several figures of the draw- ings.

In the accompanying drawings, Figure 1 shows my invention in front elevation; Fig. 2 is a front elevation of the lower extremity of the device, the same being shown upon an 40 enlarged scale that the details of construction may more clearly appear; and Fig. 3 is a transverse section of the device on the line A—B of Fig. 2, looking in the direction of the arrows.

The rod proper, which, in the accompa- 45 nying drawings, is denoted by the numeral 1 is preferably fashioned from resilient metal and, as shown in Fig. 3, is relatively thin. Adjacent its upper end 3, the rod is pro- 50 vided with an opening 4 whereby it may be suspended from a support. The rod is pro- vided with a series of openings 5 and 6, ex- 55 tending entirely through the device in its shorter dimension, and disposed in spaced parallel lines stretching substantially from one end of the device to the other. The

aligned openings 5 are located relatively near to one edge of the rod, while the openings 6 are disposed substantially along the longitudinal center of the instrument. It is to 60 be understood that these openings 5 and 6 may be made in a variety of ways but, in the present instance, I have located the openings 5 half way between the openings 6, the spaces 7 between the openings being equal, 65 since the openings are adapted to serve as graduations upon the rod. The openings 5 and 6 are provided with laterally extending 70 grooves 8 located in one face of the rod and extending outwardly to the edge thereof, these grooves 8 constituting graduations along the face of the rod. The diameters of the openings 5 and 6 will be determined by the character of the liquid which is to be measured but it is to be understood, that, in 75 any case, the diameters are to be sufficiently small to retain the liquid in the openings by capillary attraction.

Graduations, denoted by the numeral 10 may be inscribed along the face of the rod 80 and any arbitrary system of numbering may be employed. When the device is to be used continuously in the same vessel, the rod may be placed in the vessel and a given quantity of liquid may be introduced thereinto. The 85 height of this liquid upon the rod may then be noted and the openings 6 and 5, together with the grooves or channels 8, will indicate fractional parts of the volume which has been poured into the receptacle to rate the 90 rod.

I regard it as of importance, that the openings 5 and 6 extend entirely through the rod. By this construction, after the device has been used to ascertain the amount of liquid 95 in a given receptacle, one end of the device may be grasped in the hand, the other end thereof being struck smartly against any convenient obstacle, whereby the liquid held in the openings 5 and 6 will be projected from the rod, an inversion or turning of the rod being unnecessary. Moreover, since the rod is fashioned from resilient material, by grasping the extremities of the rod and bending the same slightly, the equilibrium 100 of the liquid within the openings 5 and 6 will be disturbed to such an extent that it will fall out of the openings in which it has been confined hitherto.

The openings 5 and 6 together with the 110 channels or grooves 8 serve to indicate the height of the liquid, and, by striking the rod

upon its edge, the openings 5 and 6 may be quickly and thoroughly drained, through the channels 8, the liquid flowing downwardly through the channels 8 when the rod is thus struck, instead of spattering out of the apertures in which it is confined. Moreover, by grooving the rod transversely as denoted by the numeral 8, the same may be bent more easily, so that as hereinbefore described, the equilibrium of the liquid within the apertures 5 and 6 may be disturbed, to drain the rod.

Having thus described my invention, what I claim as new and desire to secure by Letters Patent is:—

1. An ullage rod provided with openings extending entirely therethrough, and with superficial channels leading from the openings to the edge of the rod.

2. A resilient ullage rod provided with 20 openings extending entirely therethrough, and with superficial channels leading from the openings to the edge of the rod.

In testimony that I claim the foregoing as my own, I have hereto affixed my signature 25 in the presence of two witnesses.

WINFIELD L. DINSMOOR.
